UNITED STATES PATENT OFFICE

FLOYD S. HARTWELL, OF CLEVELAND, OHIO

PORTABLE BORING MACHINE

Application filed September 14, 1926. Serial No. 135,407.

This invention relates to boring or reaming bars especially adapted for use in providing smooth, round bores in the cylinders of air compressors, although not restricted to such use.

Briefly stated, an important object of the invention is to provide novel and simply operated means by which a reamer may be properly positioned and held in line to ream or bore the cylinders of an air compressor even though the main bearings of the compressor which receive the forward pilot trunnions may be slightly above or below the center lines of the cylinders.

15 A further and equally important object is to provide a reamer in which the shank thereof is provided with a universal joint so that in case the driving element is not positioned in exactly the right place the 20 shank of the cutter will not be discarded and the reamer caused to make an untrue cut.

Other objects and advantages will be apparent during the course of the following 25 description.

In the accompanying drawings forming a part of this application and in which like numerals are employed to designate like parts throughout the same,

30 Figure 1 is a side elevation of the improved rotary cutter applied, the forward pilot thereof being shown in section;

Figure 2 is a horizontal sectional view through the forward pilot mechanism;

35 Figure 3 is a vertical transverse sectional view through the forward pilot mechanism;

Figure 4 is a perspective of a rear pilot embodied in the invention;

40 Figure 5 is a perspective of a centering bar embodied in the invention;

Figure 6 is a sectional view through a compressor, the view illustrating the improved means by which the forward pilot is properly positioned preparatory to the application 45 of the rotary cutter.

In the drawings wherein for the purpose of illustration is shown a preferred embodiment of the invention, the numeral 5 designates the crank case of an air compressor

and the numerals 6 designate the cylinders of the air compressor.

Reference to Figure 6 will clearly show that the crank case is provided with alined bearings 7 to receive the journals of a crank shaft not shown. A line extending centrally through the bearings 7 will, of course, be exactly at a right angle to the axes of the cylinders 6, but such line may not bisect the axes of the cylinders. A line extending centrally through the bearings 7 may be slightly above or slightly below the axes of the cylinders and thus a pilot mechanism would not ordinarily be properly positioned when applied to the bearings 7 unless a special 65 adjusting mechanism is employed.

At this point, it might be stated that practically all street cars, interurban cars and locomotives are equipped with a motor driven air compressor, usually of the twin cylinder or duplex type.

These compressors may run from two to four years on a street car or locomotive and then have to be removed and given a thorough overhauling. A part of the overhauling operation consists in refinishing the piston receiving cylinders. If the system is that of reaming to standard oversizes the practice followed is to ream the first time to .010". The second time the cylinder is 80 reamed to .020". The third ream is to .030" and so on until the cylinders have been reamed $\frac{1}{8}$ " oversize after which the cylinders are bored to $\frac{3}{16}$ " oversize and a cast iron bushing with a flange fitted into the outer face 85 of the cylinder is pressed into the cylinder and the inside bore reamed back to the original diameter of the cylinder.

It might be added that no satisfactory system has so far been devised to enable the 90 street car repair men to properly ream or bore these cylinders in their own shops. As a result they have sent the air compressors to outside concerns which specialize in regrinding automobile cylinders and the cylinders of the air compressors are ground at approximately \$12 each if the cylinder is approximately 4.750" in diameter.

To further explain the difficulties in the way of the successful refinishing of the 100

cylinders, it might be added that in the process of manufacture of an air compressor the bearings for the reception of the journals of the crank shaft are at perfect right angles to the cylinder bores and parallel with the flat bottom milled surfaces of the securing lugs or feet by which the compressor may be secured to the street car or locomotive.

It is a comparatively simple matter to 10 extend the bearings for the crank shaft exactly at right angles to the axes of the cylinders, but a line extending centrally through the bearings may not absolutely coincide with a line bisecting the centers of both 15 cylinders. In other words, the crank shaft when applied may be $\frac{1}{2}$ " above the center line of the cylinders or $\frac{1}{2}$ " below the center lines of the cylinders without affecting the 20 operation of the efficiency of the compressor. While this difference does not affect the operation of the compressor, it is a great disadvantage when reborning or re-reaming the cylinders, especially if pilot guides are to be fastened into the crank shaft bearings for 25 the reception of the forward pilot of the reamer or boring bar.

As previously stated, it is an object of this invention to provide simple and easily adjusted means whereby the rotary cutter, be 30 it a boring or reaming bar, may be properly positioned for making the desired cut even though the center line of the bearings of the compressor is above or below a line bisecting the axes of the cylinders.

35 In carrying out the invention a boring bar or reaming bar head 10 is provided with a shank 11, the rear portion of which may be provided with a universal joint 12 by which the shank and the cutter head may 40 operate undisturbed even though there is an irregularity in the drive as will be appreciated.

With reference to Figure 1, it will be 45 observed that a rear pilot 16 is provided with an elongated sleeve 17 to receive and guide the shank 11 of the cutter. The pilot 16 is provided with attaching flanges 19 adapted to be secured by bolts to one of the annular flanges 20 of the cylinders of the 50 air compressor. When the rear pilot is applied the shank 11 and the cutter head will be accurately piloted through the cylinder to make a proper cut as will be described. Of course, a forward pilot to be described 55 in detail effectively cooperates in holding the cutter head in position while the cutter head is turning.

The cutter head 10 is provided with an integral pilot bar 26 adapted to be selectively extended into locating bushings 28, the forward portions of which are threaded into the attaching members 29.

In carrying out the invention the attaching members 29 are made rectangular in outline and are adjustably carried by a locating

block 32. The locating block 32 consists of top and bottom plates 33, end trunnions 34 having attaching portions 36 secured between the plates 33 by cap screws 37 or other suitable fastening devices. A partition block 35, secured by screws 37 has opposite faces in flat contact with plates 33 and its sides are spaced equidistant from portions 36.

70 Figure 3 clearly illustrates that the attaching portions 29 of the locating bushings 28 may be moved in the direction of the plates 33 by set screws 40 carried by the plates 33 and having their forward ends engaged with opposite sides of the attaching portions 29. Suitable lock nuts 46 may be employed to 75 secure the set screws in position. It is believed to be clear that the set screws 40 provide a means whereby the pilot bushings or locating bushings 28 may be properly positioned with respect to the cylinders 6 to be 80 finished or refinished even though the crank 85 bearings 7 which receive the trunnions 34 are above or below center with respect to the axes of the cylinders.

85 Particular attention is directed to Figures 2 and 3 which clearly illustrate that tongue and groove connections 50 hold the attaching portion 29 against endwise movement between partition 32^a and end walls 36 in the locating block, but at the same time permit the attaching portion to be moved toward 90 walls 33 under the influence of the set screws 40.

95 In use, the locating block is applied as illustrated in Figure 6 and a centering disc 60 and a centering stem 61 having a tapered plug 62 are applied to one of the cylinders. More specifically, the disc 60 is positioned in the forward portion of one of the cylinders and the plug 62 is then introduced into that 100 cylinder so that the stem 61 extends through the centrally arranged opening in the disc 60. When the stem is applied as shown in Figure 6 the locating bushings 28 which receive the forward portion of the stem 61 will 105 be properly positioned, after which it may be secured in place by the associated set screws 40. When one of the locating bushings 28 has been properly positioned and locked in place preparatory to the use of the 110 rotary cutter, the stem 61 and the disc 60 are removed and applied to the other cylinder for adjusting its locating bushing 28, after which the second locating bushing 28 may be locked in place by the associated set 115 screws 40. When the two bushings 28 have been locked in place the caps of the bearings 7 may be fastened lightly in place to hold the trunnions 34 and the reaming or 120 boring operations started. During the reaming or boring operation in one cylinder the stem 61 and associated parts is allowed to 125 remain in the other cylinder. In fact, when it is desired to ream the second cylinder the stem 61 is removed from that cylinder and 130

placed in the cylinder just reamed so as to be sure of an absolutely accurate cut.

Having thus described the invention, what is claimed is:

5. 1. A cylinder boring device adapted for the machining of a crank case having a plurality of cylinders and opposed crank shaft bearings whose axes are alined in a plane at right angles to the axes of the cylinders, said 10 device comprising a rotary cutter having a forwardly extending pilot, a locating block having trunnions adapted to be secured in said bearings, carriers slidably mounted in said block and substantially alined with the 15 respective cylinders, said carriers being independently adjustable in a plane at right angles to the axes of their respective cylinders, said carriers having guide means to receive said pilot, and centering means positionable in one of said cylinders to engage in the guide of the carrier associated therewith to hold the locating block in a set position at right angles to the axes of the cylinders while another cylinder is being 20 bored.

2. The combination set forth in claim 1 and said guide means of said carriers comprising a sleeve threaded thereinto, and the carriers having a bore communicating with the bore 25 of said sleeve.

3. A cylinder boring device adapted for the machining of a crank case having a plurality of cylinders and opposed crank shaft bearings whose axes are alined in a plane at 35 right angles to the axes of the cylinders, said device comprising a rotary cutter, having a forwardly extending pilot, a locating block having trunnions adapted to be secured in said bearings, carriers slidably mounted in said block and substantially alined in one direction with the respective cylinders, said carriers being independently adjustable in a plane at right angles to the axes of their respective cylinders, said carriers having 45 guide bushings extending laterally of the axis of the bearings and toward the cylinders, and centering means positionable in one of said cylinders to engage in the guide bushing of the carrier associated therewith whereby to hold the locating block in set position 50 at right angles to the axes of the cylinders while another cylinder is being bored.

In testimony whereof I affix my signature.
FLOYD S. HARTWELL.
